VAPOR PHASE CRACKING PROCESS

Maurice B. Cooke and Hermann Claus Schutt,
New York, N. Y., assignors to Alco Products,
Incorporated, New York, N. Y., a corporation
of Delaware

Application March 12, 1932, Serial No. 598,506

6 Claims. (Cl. 196—66)

Our invention relates to a vapor phase cracking process, and more particularly to a process in which oil in the vapor phase is cracked by a heated heat carrier gas.

5 The combustion gas has a specific heat of about .25, whereas refinery gas has a specific heat of about .65. It will be appreciated that, if refinery gas is used to carry the heat for the pyrolytic conversion, it will require a smaller 10 weight of heated gas to treat the given weight of charging stock due to the higher specific heat.

One object of our invention is to provide a process for the cracking of hydrocarbons in the vapor phase by heated gases in which the quantity 15 of gases which have to pass through the reaction and fractionating zone is reduced.

Another object of our invention is to provide a process in which the carrier gas is heated by indirect heat exchange and in which means are 20 provided for controlling the temperature of the heat carrier gas within close limits by tempering.

Still another object of our invention is to provide a vapor phase cracking process in which a heated heat carrier gas is used to supply the 25 cracking heat and which is flexible of control and efficient in operation.

Still another object of our invention is to provide a process in which the reaction is checked by means of shock chilling in order to prevent 30 over-cracking.

Other objects of our invention will appear from the following description.

The figure shows a diagrammatic view of one embodiment of the process of our invention.

35 In general, our invention consists in burning fuel in a furnace. If desired, a surface combustion burner may be used to generate hot gases of combustion. The radiant heat generated within the furnace is employed to heat the hydrocarbon oil to be cracked. Refinery 40 gas is withdrawn from the gas main and passed in indirect heat exchange with the flue gases and then passed through a coil exposed to the convection heat of the hot combustion gases.

45 We provide means for introducing a quantity of carbon dioxide and steam at spaced points in the coil in order to control the outlet temperature and the pyrolytic reaction of the heated 50 gases. We have found that a temperature of about 1500° F. will give the best results. At this temperature, the heated gases when admixed with the oil vapors, will result in a mixture temperature of about 1050° F. to 1150° F. at 55 which temperature the cracking will take place

rapidly on account of the atomized state of the vapors to be cracked.

The charging stock is pumped through suitable heat exchangers into an accumulator tank from which it is withdrawn and passed through the vaporizing coil of the furnace. In this coil the incoming charging stock is heated to a vaporizing temperature. We vaporize the heated charging stock in a flash evaporator and pass the vapors into direct contact with the heated 10

gases to thoroughly commingle them. The commingled gases and vapors will react due to the temperature and the pyrolytic decomposition of the vapors will take place to form gasoline-like hydrocarbons in the reaction or cracking 15 zone. Inasmuch as the reaction will take place rapidly at a temperature of 1050° F. we propose to stop the reaction to prevent over-cracking by quenching sprays. It is to be noticed that we provide an increase in cross sectional area in 20 order to prevent the building up of pressure.

The products, after being chilled, pass into a tar separator. The tar leader quenching oil is drawn through a cooler and pumped to storage and may be used for fuel oil. The vapors and 25 gases are passed through a sectional entrainment condenser through a heat exchange evaporator in which the heat of the products is used to vaporize water to form steam, and then into a fractionating tower. The condensate from the 30 entrainment condenser collects in suitable pockets and may be passed either into the separator or into a fractionating tower depending upon their nature and character.

The reflux condensate from the fractionating 35 tower is withdrawn and pumped through a cooler in order to reduce the temperature thereof to render it suitable as a quenching medium.

After passing through the cooler, it is passed through the sprays in order to be used in the 40 chilling zone. A portion of the reflux condensate of the fractionating tower may be diverted into the accumulator for recycling. The vapors and gases withdrawn from the fractionating 45

tower are cooled and passed into a separator from which the water is withdrawn. The condensate is withdrawn from the separator as gasoline and passed to storage. The uncondensed gases from the separator are compressed and cooled and passed into an absorber where they 50 are mixed with a lean oil as in a gasoline absorption process.

A fat oil drawn from the bottom of the absorber is passed into a steam still to recover the gasoline fractions. The fixed gas is passed into 55

a gas main to supply fuel for the burner of the furnace.

More particularly referring now to the drawing, gas from the gas main 1 is withdrawn through valve controlled line 2, for combustion in burner 3. The radiant heat generated by the burner will be absorbed in part by the cracking stock in heating coil 4 the function of which will be hereinafter more fully described. The gases of combustion pass around the bridge wall 5 and go past the coil 6 and out through the flue connection 7 and the chimney 8. It is to be understood that, while I have shown coils, any suitable type of pipe still equipment may be employed.

A branch line 9 supplies refinery gas to the flue heat exchanger 10 in which the refinery gas passes in heat exchange with the gases passing through the flue 7. After being preheated, the refinery gases pass through line 11 and into coil 6 through which they flow in heat exchange with the hot combustion gases. A connection 12 supplies carbon dioxide under the control of valve 13 for varying the quantity of gases and has a further function of acting as a reaction and a temperature control. If the temperature of the heated gases entering the mixing zone be too high, by opening valve 13 the temperature may be reduced and, on the other hand, if the temperature of the gases entering the mixing zone be too low, the valve 13 may be partially or entirely closed. Line 14 controlled by valve 15 supplies steam to the coil 6. The steam acts both as a reaction controlling and a tempering agent and as an additional heat carrier due to its high specific heat. The heat-carrier gas leaves the coil 6 and passes into the mixing zone 16 at a temperature of about 1500° F. The products leaving the coil 6 will be hereinafter referred to as the heat-carrier gas and will include the refinery gas, the carbon dioxide and whatever steam may be present.

Hydrocarbon oil, being charged through line 17, is pumped by pump 18 through line 19 through heat exchanger 20, through line 21, into accumulator 22. From the accumulator 22 the fresh feed and recycle oil are pumped by pump 23 through heat exchanger 24 and are pumped through line 32, it being understood that valves 33 and 34 are open and valve 35 is closed or partially closed. The charge passes from line 32 through the tubing 36 of the sectional entrainment condenser 37 and leaves said condenser through line 38 passing through valve 33 into line 39, through the vaporizing heating coil 4. The heated charging stock leaves the coil 4 through line 41 and passes into the flash evaporator 42. The unvaporized oil from the flash evaporator may pass through line 43, through valve 44, through line 45, through cooler 49, where it is pumped by pump 50 to storage as fuel oil, or it may be returned to the accumulator for recycling. The vapors from the flash evaporator will pass through line 51 and be discharged into a mixing zone 16. Valve 51' controls the vapor flow.

The hydrocarbon vapors entering the mixing zone through line 51 will be commingled and mixed with the heated heat-carrier gas to form a mixture having a resultant temperature of about 1100° F., and cracking or pyrolytic decomposition will take place rapidly.

As cracking takes place, the volume of the products will increase and, in order to prevent

the building up of pressure, a cracking chamber of progressively increasing volume is provided.

Inasmuch as the cracking will take place very rapidly, at the temperature of 1050° F. we resort to shock chilling or quenching to reduce the temperature of the products of reaction from 1100 to 700° F. We do this by means of oil sprays 53, 54, and 55, oil spray 55 being located in the tar separator 57. The temperature of 700° is low enough to prevent any further reaction and high enough to permit the distillate to escape in the vapor state into the fractionating tower. The heavy, tarry fuel oil, however, will accumulate in the bottoms of the separator 57. These heavy bottoms are withdrawn through line 58 which joins with line 45 and permits the fuel oil bottoms to be passed through the cooler 49 to fuel oil storage.

The vapors and gases from the tar separator 57 pass overhead through line 59 into a sectional entrainment condenser 37, whence they will pass in counterflow relation to the incoming charging stock which is passing through tubes 56. The hot vapors will be cooled considerably by the incoming charging stock which in turn will be heated. The entrainment condensate is allowed to collect in compartments 60, 61, and 62. The condensate may be withdrawn from the respective compartments and selectively passed into the separator or fractionating tower through lines 63 and 64 respectively. The condensate may be supplied as desired by means of valves 65, 66, 67 and 68, so that all or part of the condensate collected in the sectional entrainment condenser 37 may be passed to either the separator or the fractionating tower as desired and depending upon the nature of the condensate. The vapors and gases leave the sectional entrainment condenser through line 69 and pass into the fresh water evaporator 25. Fresh water is admitted through valve controlled line 26 and passes through the tubes 27 of the fresh water evaporator 26 in heat exchange relationship with the hot vapors entering through line 69 from the sectional entrainment condenser. The heat of the vapors will be sufficient to convert the water into steam which leaves the tubes 27 through line 28 which passes into line 14 for use as injection into the coil 6 as heretofore described. The vapors thus further cooled are withdrawn through valve controlled line 29 and pass into the fractionating tower 70. The condensate formed in the bottom of the evaporator 25 is withdrawn through valve controlled line 30 and likewise pass into the fractionating tower 70.

The reflux condensate from the fractionating tower is withdrawn through line 71 and passed partly through heat exchanger 24, through line 72, through cooler 74 and into line 76, which terminates in a manifold for the quenching sprays. The quenching oil leaves line 76 through valve controlled lines 77, 78 and 80. A portion of the reflux condensate from the fractionating tower is diverted through valve controlled line 81 and allowed to pass into the accumulator for recycling.

The vapors and gases from the fractionating tower passes through line 82, through heat exchanger 20, through cooler 83, through line 84 into separator 85. Water from the bottom of the separator is withdrawn through line 86. The gasoline-like hydrocarbons are withdrawn through line 87 and passed to storage. A por-

tion of the oil is withdrawn through line 98 and pumped by pump 99 through line 100 into the fractionating tower 70 as reflux. The gas from the separator will contain a quantity of 5 gas rich in gasoline-like hydrocarbons. Accordingly, I propose to withdraw it through line 88 and compress the gas in compressor 89, pass it through cooler 90, through line 93 and into the gasoline absorption tower 94 where it is 10 scrubbed by lean oil entering through line 95. The fixed gas is withdrawn through line 96 into gas main 1. The fat oil from the bottom of the absorption tower 94 is withdrawn through line 97 and passed to a steam still for the distillation therefrom of the gasoline-like hydrocarbons.

It will be appreciated that my process has many advantages. By using a heat carrier gas having a higher specific heat than ordinary 20 combustion gases, I am enabled to crack in the vapor phase by hot gases of combustion and at the same time avoid excessive size of fractionating and absorption equipment due to the fact that a small quantity of gases will be necessary 25 to crack a given amount of charging stock. We provide an efficient means for cracking hydrocarbon vapors by heated gases and, at the same time, we provide a process which is flexible of control. The thermal efficiency of our process 30 is exceedingly high. The temperature of the heated heat carrier gas, the temperature of the quenching oil, and hence the temperature of the reaction may be controlled within close limits.

35 We are enabled by our process to crack hydrocarbon oil in the vapor phase and obtain a gasoline-like hydrocarbon suitable for use as a motor fuel and having an exceedingly high anti-knock value. We may use a portion of the gas formed in our process for other purposes where 40 gaseous fuel may be needed and as the carrier gas. It will be noted that the cracking reaction takes place in the pure vapor phase, it being impossible for any hydrocarbon oil which is not 45 in the vapor form to be present. This insures the absence of the danger of the formation of coke or carbon deposits within our cracking zone. It will be understood, of course, that suitable lagging is provided throughout the piping 50 and the piece of apparatus used in our process to prevent the loss of heat by radiation.

It will be understood that certain features, sub-combinations and operations are of utility and may be employed without reference to other features and sub-combinations. This is contemplated by and is within the scope of our 55 claims. It is further obvious that various changes may be made in details within the scope of our claims without departing from the spirit of our invention. It is, therefore, to be understood that our invention is not to be limited to the specific details shown and described.

By this method of cracking hydrocarbons in the vapor phase, in which the hydrocarbons are 60 combined with the combustion gases, the latter being maintained at selected, controlled temperatures of reaction, a motor fuel having a high octane number and high antiknock value is obtained. The process eliminates parasitic cracking 65 which accompanies conventional cracking methods, in which the hydrocarbons are converted in tubular containers and heated by external circulation of the combustion gases thereabout. The intimate mixture of the combustion gases with the hydrocarbon vapor pro-

duces a distribution of heat impossible with the conventional tubular cracking processes.

Having thus described our invention, what we claim is:

1. The process of converting hydrocarbons in the vapor phase into gasoline-like hydrocarbons of lower molecular weight including the steps of heating the hydrocarbon oil to be converted in an elongated confined stream, flashing said heated oil into vapors in an evaporating stage, separately withdrawing the vaporized and unvaporized portions from said evaporating stage, simultaneously with said vaporizing steps heating a heat carrier gas by indirect heat exchange, controlling the temperature and reaction of said 10 heat carrier gas by injecting cooler inert gases thereto during said gas heating step, commingling said heated heat carrier gas with the hydrocarbon vapors withdrawn from said evaporating stage in a zone entirely free of liquid to permit 20 pyrolytic decomposition of said hydrocarbon vapors to take place whereby gasoline-like hydrocarbons having a lower molecular weight are produced.

2. The process of converting hydrocarbons in the vapor phase into gasoline-like hydrocarbons of lower molecular weight including the steps of heating the hydrocarbon oil to be converted, in an elongated confined stream, flashing said heated oil into vapors in an evaporating stage, simultaneously heating a heat carrier gas by indirect heat exchange, controlling the temperature to which said gas is heated and the pyrolytic reaction by admixture therewith during said gas heating step, of cooler inert gases in order to 35 bring the exit temperature of said carrier gas to about 1500° F., admixing the vapors withdrawn from the evaporating stage with said heated heat carrier gas whereby the temperature of the mixture will be substantially between 1050° F. and 40 1100° F., allowing a pyrolytic decomposition of said vapors to take place in a zone entirely free of liquid whereby gasoline-like hydrocarbons having a lower molecular weight are produced, stopping said reaction by spraying oil after the 45 reaction has progressed to a desired extent whereby overcracking is prevented.

3. The process of converting hydrocarbons in the vapor phase into gasoline-like hydrocarbons of lower molecular weight including the steps of heating the hydrocarbon oil to be converted in an elongated confined stream, flashing said heated hydrocarbons into vapors in an evaporating stage, simultaneously heating a heat carrier gas by indirect heat exchange, controlling the temperature to which said gas is heated and the pyrolytic reaction by admixture therewith during said gas heating step of cooler inert gases in order to bring the exit temperature of said carrier gas to about 1500° F., admixing the 50 vapors withdrawn from the evaporating stage with said heated heat carrier gas whereby the temperature of the mixture will be substantially between 1050° F. and 1100° F., allowing a pyrolytic decomposition of said vapors to take place 55 in a zone entirely free of liquid whereby gasoline-like hydrocarbons having a lower molecular weight are produced, stopping said reaction by spraying oil into contact with the mixture of hot gases and vapors after the reaction has progressed a desired extent whereby over-cracking is prevented, fractionating the products of reaction and withdrawing the reflux condensate from the fractionating stage for use as a quenching oil.

4. The process of converting hydrocarbons in the vapor phase into gasoline-like hydrocarbons of lower molecular weight including the steps of heating the hydrocarbon oil to be converted in an elongated confined stream, flashing said heated hydrocarbons into vapors in an evaporating stage, simultaneously heating a heat carrier gas by indirect heat exchange, controlling the temperature to which said gas is heated and the 5 pyrolytic reaction by admixture therewith during said gas heating step of cooler inert gases in order to bring the exit temperature of said carrier gas to about 1500° F., admixing the vapors withdrawn from the evaporating stage with said 10 heated heat carrier gas whereby the temperature of the mixture will be substantially 1050° F., allowing a pyrolytic decomposition of said vapors to take place in a zone entirely free of liquid whereby gasoline-like hydrocarbons having a 15 lower molecular weight are produced, stopping said reaction by spraying oil into contact with said hot gases and vapors after the reaction has progressed to a desired extent whereby over-cracking is prevented, fractionating the products 20 of reaction and withdrawing the reflux condensate from the fractionating stage for use as a quenching oil, withdrawing the vapor and gases from the fractionating stage, cooling said vapors and gases, withdrawing the condensate formed in 25 the vapor and gas cooling stage and subjecting the uncondensed products to gasoline absorption treatment, and withdrawing the fixed 30 gases from the gasoline absorption operation for use as the heat carrier gas and as a fuel gas.
5. The process of converting hydrocarbon oils into gasoline-like hydrocarbons of lower molecular weight including the steps of heating the 25 hydrocarbon oil to be converted, flashing the heated oil into vapors and unvaporized oil in an evaporating stage, separately withdrawing the vapors and unvaporized oil from said evaporating stage, simultaneously with said vaporizing 30 steps heating a heat carrier gas in an elongated confined stream, commingling said heated heat carrier gas with hydrocarbon vapors withdrawn from said evaporating stage to permit a pyrolytic 35 decomposition of the vapors to take place whereby gasoline-like hydrocarbons are formed and controlling the reaction by governing the temperature of the heated heat carrier gas by injecting a cooler gas or vapor into the elongated 40 confined stream while said stream is being heated.
